UNITED STATES PATENT OFFICE.

ALEXANDER DOMINICK, OF NEW YORK, N. Y.

DESIGN FOR THE ORNAMENTATION OF HANDLES FOR SPOONS, &c.

SPECIFICATION forming part of Design No. 18,614, dated September 18, 1888.

Application filed July 3, 1888. Serial No. 278,970. Term of patent 14 years.

To all whom it may concern:

Be it known that I, ALEXANDER DOMINICK, a citizen of the United States, residing at New York, in the county and State of New York, 5 have invented and produced a new and original Design for the Handles of Spoons, Forks, Knives, &c.; and I do hereby declare the following specification, taken in connection with the accompanying photographic illustrations, forming a part of the same, to be a description thereof.

One of said illustrations is a view of the face or front and the other of the back of a spoon whose handle exhibits my design. The outline of the handle is fiddle-shaped. The face or front has a representation in relief, composed of irregularly-placed scrolls α , extending from the narrow portion or neck of the spoon to the end of the handle, and interspersed among the scrolls α corollas or flowers

with open petals b . The back of the handle exhibits a grooved bead, c , inclosing a plain surface, d , and at intervals scrolls α , projecting inwardly from the grooved bead, the latter terminating at the end of the handle with 25 scrolls α .

I claim—

1. The design for surface ornamentation of the front face of handles of spoons, forks, or knives, as shown and described. 30
2. The design for surface ornamentation of the rear face of the handles of spoons, forks, or knives, as shown and described.
3. The design for surface ornamentation of the handles of spoons, forks, or knives, as 35 shown and described.

ALEXANDER DOMINICK.
